CONVERSION OF NORMALLY GASEOUS HYDROCARBONS

Everett Gorin, Dallas, Tex., assignor to Socony-Vacuum Oil Company, Incorporated, a corporation of New York

No Drawing. Application June 28, 1941,
Serial No. 400,296

10 Claims. (Cl. 260—673)

This invention relates to the pyrolysis of normally gaseous hydrocarbons for the production of aromatic hydrocarbons and may include the formation of light unsaturated aliphatic hydrocarbons, such as acetylene and ethylene. The invention is concerned particularly with the production of benzene from methane.

The formation of benzene, acetylene and light olefins, such as ethylene, by the pyrolysis of normally gaseous hydrocarbons, such as methane, ethane and propane, is known. However, for example, in the strictly thermal conversion of methane to benzene, the benzene only becomes quantitatively measurable at temperatures above about 900° C. By increasing the temperature the yield will show a gradual rise up to 6-10% at 1200-1300° C., and then it begins to fall off as the reaction temperature is raised still higher. Naturally, numerous attempts have been made to discover catalysts or other means for aiding the pyrolysis of methane to benzene in order that lower reaction temperatures may be used and/or the yield of benzene increased. Nevertheless, insofar as I am aware, these attempts have been rather uniformly unsuccessful.

It, therefore, is an object of my invention to provide an improved process of converting normally gaseous hydrocarbons to light aromatic hydrocarbons. Another object is to afford a process of converting normally gaseous hydrocarbons to aromatic and unsaturated aliphatic hydrocarbons, which is an improvement over strictly thermal processes for accomplishing the same results, due to my use of certain "reaction promoters." These and other objects will be apparent from the following description of my invention.

I now have found that by carrying out the pyrolysis of normally gaseous hydrocarbons, to produce aromatic and light unsaturated aliphatic hydrocarbons, in the presence of a certain class of metal halides under pyrolyzing conditions that, compared to a strictly thermal process, substantially lower temperatures may be used to obtain at least as high yields or substantially higher yields may be obtained at the same temperature.

The metal halides used under the conditions of my process are not catalysts because they enter into the reaction and are chemically changed, viz., reduced, by the reaction. Thus, for example, in the conversion of methane to benzene using stannic chloride as the promoter and assuming, for sake of simplicity, that benzene is the only hydrocarbon formed, the equation is as follows:

In conducting my research on the present process I found that if the reaction is to be carried

out feasibly at high temperatures some convenient way of removing hydrogen must be found. Furthermore, I discovered that not only must hydrogen acceptors be provided but also inducers for removing hydrogen from the gaseous hydrocarbons should be present. It appears that the metal halides of my invention perform these functions under the pyrolyzing conditions of the process whereby a substantial improvement over a strictly thermal process is obtained. Accordingly, I have designated these halides as "reaction promoters."

The reaction promoters which I have discovered are the easily reducible, heavy metal halides, and of these halides I particularly prefer the halides of mercury, lead, and tin. During the pyrolyzing reaction the metal halides are reduced to a lower halide or to the metal itself. Therefore, metal halides should not be used, which, either themselves or the products they form when reduced in the presence of hydrogen, strongly promote cracking of the hydrocarbons to carbon and hydrogen under the pyrolyzing conditions. This, in general, means that metal halides which are solids under the conditions of the process, and metal halides which form products of reduction that are solids under the conditions of the process, should not be used. It is to be noted, however, that a compound such as ferric chloride, which upon complete reduction will form metallic iron which is a strong cracking catalyst for methane, may be used if the process is regulated so that the ferric chloride is reduced only to ferrous chloride. On the other hand, cuprous chloride, although not particularly desirable, might be used even though it is reduced to metallic copper (solid below 1083° C.) because metallic copper is only a mild cracking catalyst, and any handling difficulties may be largely obviated, for example, by working with a large excess of the molten salt so that metallic copper is retained in colloidal suspension. In the broader aspects of the invention, it might be said that my reaction promoters are metal halides which are reduced under the operating conditions of my process to lower metal halides or to the metals themselves, and which neither by themselves nor through their reduction products substantially promote cracking of the hydrocarbons being treated. It appears that any such metal halide will be an effective reaction promoter in my process. However, as stated above, the presently preferred reaction promoters are the chlorides of mercury, tin and lead. These compounds and the products they yield, when reduced with hydrogen, are all liquids or vapors above 501° C. Furthermore, they show no tendency to form carbides and are non-catalytic toward cracking of the hydrocarbons. In the case of some metal bromides the amount

of promoter reduced might be quite small; nevertheless, it is essential that some reduction be obtained in all operations.

In copending application, Serial No. 580,716, filed March 2, 1945, a continuation-in-part of application, Serial No. 399,942 filed June 26, 1941, now abandoned, it is disclosed that chlorine or bromine also are reaction promoters for the pyrolysis of normally gaseous hydrocarbons. This fact affords the opportunity of using a metal halide of the above-mentioned type in combination with chlorine or bromine for promoting the pyrolysis reaction whereby the combined effect of these two reagents is obtained. It is to be understood my invention includes the use of metal halides in such combinations.

The actual operating procedure for carrying out my pyrolysis of methane in the presence of metallic halides may be quite similar to the technique used heretofore for the strictly thermal pyrolysis of methane. The only necessary difference is that instead of the hydrocarbons being subjected to the high temperatures only, they are subjected to these high temperatures while in the presence of my metal halide reaction promoters. Thus, for example, when employing a stannic chloride promoter, the methane, after removal of sulfur, if necessary or desired, may be bubbled through a stannic chloride saturator, which is suitably heated, and then the resulting reaction mixture of hydrocarbon and stannic chloride vapors may be passed through a conventional thermal pyrolysis converter, such as a quartz, Monel metal, or porcelain reactor. The temperature within the converter, however, may be substantially less for my process, as set forth hereinafter, than for straight thermal pyrolysis of methane. Further, it is to be understood that the total yield of benzene may be increased by further pyrolysis of product gases from which benzene has been removed.

The temperature of operation should be above about 500° C., in fact, when converting methane I recommend a temperature above about 600° C. In my preferred operations I employ a temperature between about 600 and about 1200° C. However, if desired, higher temperatures may be used, particularly when interested in acetylene production. Thus, for instance, at temperatures up to 1200° C. the yields obtained by my process are in every instance substantially superior to those obtained at corresponding temperatures in the absence of a promoter. Therefore, from a practical standpoint, it is important to note this increase in yield is obtained and that my process also makes possible, for the first time, the production of substantial amounts of benzene from methane at temperatures below 1000° C.

I have found that when, for example, a mixture of methane and a fluid metal halide is pyrolyzed the metal halide is reduced and the methane is simultaneously converted to benzene, naphthalene, anthracene and other condensed aromatic hydrocarbons, acetylene and ethylene, while some carbon is formed in addition. The methane conversion may be regarded as the superposition of two reactions. First of all, the methane reduces the halide and is simultaneously converted to benzene and the other products listed above. Then, in general, the occurrence of the first reaction induces an additional decomposition of the methane wherein hydrogen is split out and any or all of the above products, such as benzene, etc., are formed.

In the first reaction, the metal halide acts as a reagent for the conversion of methane. This re-

action usually proceeds at a very much higher rate than the direct thermal conversion of methane. Thus, in my experiments I have found that I am able in my process to obtain a substantial conversion of the methane which results in a complete reduction of the metal halide by the methane under reaction conditions where methane alone suffered practically no decomposition. The amount of the induced decomposition relative to the amount of this direct reaction of methane with the metal halide is greater the higher the temperature and the higher the ratio of methane to metal halide used.

This same relationship between induced and non-induced reactions holds also for similar reactions wherein liquid aromatic hydrocarbons, acetylene and olefins are simultaneously produced from other normally gaseous hydrocarbons.

Since the induced decomposition of methane always involves the formation of hydrogen while the non-induced reaction does not, a quantitative measure of the ratio of the induced to the non-induced reactions may be obtained by taking the ratio of the number of mols of free hydrogen produced to the number of mols of hydrogen accepted by the metal halide.

Thus, for example, I found that when a methane-mercuric chloride mixture containing 15 mol percent of mercuric chloride was passed through a pyrolysis tube, the outer periphery of which was maintained at 925° C., at a rate sufficient to cause complete reduction of the halide to hydrogen chloride that the ratio of the induced to the non-induced reaction was 1:3. When lower concentrations of the halide were used the ratio increased. Accordingly, I prefer to use a low concentration of metallic halide promoter, say, between about 0.1 and about 20 mol per cent, and particularly those ranges below about 10 mol per cent. However, it is to be understood that amounts of promoter above 20 mol per cent may be used even though little or none of the above-mentioned induction reaction occurs.

In carrying out the process, it may be found profitable in some cases to use superatmospheric pressure, whereby a better induction effect may be obtained, even though results at atmospheric pressure are entirely practical.

The invention is further illustrated by the data shown in the table below, wherein conditions and results of typical operations are set forth. The real and substantial improvement effected by the use of my reaction promoters is clearly brought out by these data.

Table

Methane rate, liter/hr.	Percent catalyst	Reaction time, sec.	Temp., °C.	Total pres.	Mol percent light oil (mainly benzene)
				Atmospheres	
15.0	None	120	890	1	Trace
13.5	3% SnCl ₄	69	876	1	5.5
60.0	21% SnCl ₄	25	925	1	7.5
21.4	PbCl ₂ ¹	63	925	1	3.1
11.8	PbCl ₂ ¹	76	923	1	4.6
10.0	20% HgCl ₂	113	775	1	6.9

¹ PbCl₂ was used in the form of a liquid bath containing an excess of PbCl₂ and the methane was bubbled through the bath.

When liquid halides which are non-volatile under the operating conditions are used, it is often desirable to employ a large excess of the halide in the form of a liquid bath as was done with PbCl₂ above. In this way the excess halide not reduced, as well as the liquid reduction product, may serve as a direct heat exchange medium for the hydrocarbons.

In the present process, commercial feasibility is dependent upon a practical method of recovering or regenerating the reaction promoter, just as catalyst regeneration is essential in the usual catalytic process. This regeneration may be conducted in any suitable manner. For instance, no difficulty is experienced in the regeneration of the metal halides of my process whose reaction with hydrogen is reversible. In these cases, the halide can be regenerated, for example, by bubbling the off gas, containing HCl but freed of light and heavy oil, into the molten metal either under pressure or at a lower temperature than is used in the reaction on methane. It is interesting also to note that this reaction is exothermic, and that the pyrolysis reactions of converting methane to benzene are endothermic. Therefore, it is desirable to carry out these two operations within heat transfer relationship of each other. Halides, such as mercuric chloride, whose reduction with methane is not reversible and which do not form oxychlorides, may be regenerated, for example, by the exothermic reaction of burning the off gas, containing HCl but freed of light and heavy oil, in admixture with the metal in question.

A third regeneration method generally applicable to all my metal halide reaction promoters involves separation of the halogen acid from the pyrolysis off gases followed by catalytic oxidation of the halogen acid to the free halogen. Any of the known methods may be used to effect this catalytic oxidation. The free halogen obtained may then be contacted with the reduced form of the metal halide whereby the original metal halide is produced.

The invention has been described with particular reference to the conversion of methane to benzene for the sake of simplicity. However, it is to be understood the invention is applicable to the treatment of normally gaseous hydrocarbons generally. Moreover, it should be understood clearly that my process produces, just as does a strictly thermal process of this type, unsaturated aliphatic hydrocarbons, particularly ethylene and acetylene, as well as aromatic hydrocarbons, and that the relative ratios of these compounds in the reaction products can be varied by altering the operating conditions analogously to the manner known in the art for accomplishing this result in strictly thermal processes.

I claim:

1. The process for manufacturing light aromatic hydrocarbons and normally gaseous unsaturated hydrocarbons from normally gaseous paraffinic hydrocarbons which comprises admixing with the normally gaseous paraffin from 0.1 to 20.0 mol percent of a fluid, easily reducible heavy metal halide, maintaining the temperature of the mixture between 500° C. and about 1200° C. until reduction of said halide occurs, said

halide being selected so that under the conditions of the process its reduction product will be a fluid and so that neither it nor its reduction product will promote substantial cracking of the hydrocarbons.

5 2. A continuous process for the manufacture of light aromatic hydrocarbons and normally gaseous unsaturated hydrocarbons which comprises passing a normally gaseous paraffinic hydrocarbon in admixture with from 0.1 to 20 mol percent of an easily reducible metal halide gas at a temperature between 500° C. and about 1200° C. through a pyrolysis zone at a rate such that the contact time is at least sufficient to obtain substantially complete reduction of the highest valence state of the metallic halide, cooling the product gases, and recovering the aromatic hydrocarbons and unsaturated hydrocarbons from unconverted paraffins, hydrogen halide and metallic halide reduction product.

10 3. A continuous process for the manufacture of light aromatic hydrocarbons and normally gaseous unsaturated hydrocarbons which comprises passing methane in admixture with from 0.1 to 20 mol percent of an easily reducible metal halide gas at a temperature between 600° C. and about 1200° C. through a pyrolysis zone at a rate such that the contact time is at least sufficient to obtain substantially complete reduction of the highest valence state of the metallic halide, cooling the product gases, and recovering the aromatic hydrocarbons and unsaturated hydrocarbons from unconverted methane, hydrogen halide and metallic halide reduction product.

15 4. The process for manufacturing light aromatic hydrocarbons and normally gaseous unsaturated hydrocarbons from methane which comprises admixing with the methane from 0.1 to 20.0 mol per cent of fluid, easily reducible heavy metal halide, maintaining the temperature of the mixture between 600° C. and about 1200° C. until reduction of said halide occurs, said halide being selected so that under the conditions of the process its reduction product will be a fluid and so that neither it nor its reduction product will promote substantial cracking of the hydrocarbons.

20 5. The process of claim 1 in which the metallic halide is a halide of mercury.

6. The process of claim 1 in which the metallic halide is a halide of tin.

25 7. The process of claim 1 in which the metallic halide is a halide of lead.

8. The process of claim 2 in which the metal halide gas is a gaseous halide of mercury.

30 9. The process of claim 2 in which the metallic halide gas is a gaseous halide of tin.

10. The process of claim 2 in which the metal halide gas is a gaseous halide of lead.

EVERETT GORIN.
